UNITED STATES PATENT OFFICE.

EDWIN E. BARNEY, OF NEW ROCHELLE, NEW YORK, ASSIGNOR TO REMINGTON TYPE-WRITER COMPANY, OF ILION, NEW YORK, A CORPORATION OF NEW YORK.

TYPEWRITING MACHINE.

Application filed December 12, 1925. Serial No. 75,062.

My invention relates primarily to line lock mechanism for typewriting machines, and its chief object is to provide new and improved mechanism of the character stated. A specific object of the invention is to improve and develop the line lock mechanism disclosed in my prior application, Sr. No. 652,683, filed July 20, 1923. Another object is to improve the mounting of the space bar of the machine. Still another object is to simplify the mounting for the escapement wheel.

To the above and other ends which will hereinafter appear, my invention consists in the features of construction, combinations of devices and arrangements of parts hereinafter described and particularly pointed out in the claims.

In the line lock mechanism disclosed in my aforesaid prior application, Sr. No. 652,683, a line lock hook was employed to lock an arm projecting from the rock shaft of the universal bar mechanism, said hook also locking a finger on a link actuated from the space bar. In other words, the line lock mechanism was effective to lock the universal bar, which in turn locked the type bars with which the universal bar cooperated, and was also effective to lock the space bar. It was found, however, in practice that although the line lock operated to prevent the type bar from printing, it was nevertheless possible under a rather heavy stroke on a printing key to force the dog rocker far enough to cause an actuation of the escapement mechanism, the consequence being that if the line lock were then released and the next letter were printed there would be a blank space preceding this letter. My present invention obviates this defect by providing a line lock for the dog rocker in addition to the type bar line lock. This new dog rocker lock is also effective to prevent the space bar and its connected train of devices from actuating the escapement mechanism, enabling me to simplify the prior construction by dispensing with the separate line lock controlled by the space bar. As a result the present construction provides both a type bar line lock and a distinct or separate line lock for the escapement, the latter line lock being effective both for the printing keys and the space bar or key. There has also been provided an improved mounting for the space bar frame

which enables it readily to be applied to and detached from its pivotal support without disturbing said support. Also, the mounting of the escapement wheel and associate parts has been simplified especially by dispensing with separate thrust collars for the escapement wheel shaft.

My invention will be more specifically described by reference to the accompanying drawings wherein:

Fig. 1 is a fragmentary front to rear vertical sectional view taken about centrally of a No. 60 Smith Premier typewriting machine to which the preferred form of my invention is shown as applied, only such parts of the machine being shown as are necessary to a full understanding of the invention.

Fig. 2 is an enlarged sectional view taken axially of the escapement wheel and showing said wheel and associate parts.

Fig. 3 is a fragmentary transverse vertical sectional view taken on a vertical plane in rear of the platen.

As appears from the drawings, the main frame of the machine comprises a rectangular base portion 1 from which rise posts 2 supporting a top plate 3. The top plate supports brackets (not shown) to which are secured fixed track bars or guide rails 4 and 5 that are oppositely grooved and cooperate through anti-friction rollers 6 with the grooved rear bar 7 of a travelling carriage. Said carriage further includes end bars 8 that support a rotary cylindrical platen 9. Cooperative with the front face of the platen 9 are printing instrumentalities or type bars 10, arranged in an arc below the platen and pivoted on a common pivot wire 11 which is mounted on a support or segment 12, vertically arranged and mounted to shift up and down to change case, the type bars being arranged in radial slots 13 in said segment. Each type bar has an actuating train comprising a link 14 and a sub-lever 15, the sub-levers being slotted at 16 to cooperate with a fixed rod 17, and being pivotally supported at 18 on key levers 19 cooperative with a fulcrum plate 20. Each key lever is provided with a key or button 21 and a restoring spring 22. When a key lever is depressed it operates through the described train of connections to swing its type bar up and cause the lower case type thereon to coact with the platen.

In order to change case, one of the shift keys, not shown, is operated to shift the segment 12 downward together with the type bars thereon, so that thereafter, when a printing key 21 is actuated, the upper case type of the associate type bar will coact with the platen.

The platen carrier or carriage 7, 8 is constantly urged leftward by a carriage motor 10 or spring drum (not shown), such movements being controlled by carriage feeding devices that are connected with the carriage through a spring-pressed feed rack 23 pivoted on the carriage. Said rack normally 15 cooperates with a feed pinion 24 which is fixed to or integral with the forward end portion of a horizontal shaft 25 that is supported near its front and rear ends on the parallel upwardly extending portions, numbered respectively 26^a and 26^b, of a two-part bracket member 26 that extends downward through a gap in the top plate 3 and is detachably fixed to the under side thereof. Supported on the shaft 25 is an escapement 20 wheel 27 formed with radial teeth 28 and secured by a plurality of screws 29 to the flange 30 of a rotary support or quill which further comprises a barrel or sleeve portion 31 that is perforated or bored out as indicated at 32 to fit over and rotate on or with the shaft 25. Forwardly the barrel 31 is formed with a circular rib or flange 33 and its front end portion bears in the front bearing or bracket arm 26^a. The barrel 31 extends somewhat rearward from the plane of the escapement wheel entering a depression or seat 34 of a circular housing or ratchet box 35, in which are housed the usual spring pressed pawls 36 that cooperate with a ratchet 37 to give a one-way connection between the ratchet box 35 and shaft 25 on one hand and the quill 30, 31 and the escapement wheel 27, 28 on the other. The pawls 36 are pivoted on the quill and the ratchet is formed in the box 35. The ratchet box 35 is fixedly secured to the shaft 25 by set screws 38 which are threaded through the hub 35^a and abut against the shaft. The rear end portion of the shaft bears directly 45 in the rear bearing or bracket portion 26^b. Referring to Fig. 2, it will be observed that rearward endwise displacement of the shaft 25 is prevented by the feed pinion 24, said pinion being rigid with the front end of the shaft and having a boss or hub 24^a which abuts against the front upright face of the forward bearing 26^a. As a consequence, rearward displacement of the quill and escapement wheel along the shaft are prevented through coaction of the rear end of the quill with the bottom of the seat 34 in the ratchet box 35, which is fixed to the shaft 25. On the other hand, forward displacement of the quill is prevented by cooperation of its flange 33 with the front bear-

ing 26^a, thus preventing forward displacement of the shaft 25 through the coaction of the bottom of the seat 34 in the ratchet box 35 with the rear end of the barrel 31. The construction is such that separate or individual thrust collars are eliminated, while at the same time displacement of the escapement wheel and associate parts relative to their bearings is prevented, without, however, interfering with the free rotation of the wheel and said parts.

Cooperative with the escapement wheel 27, 28 are escapement dogs 39 and 40, mounted at the top of a dog carrier or rocker 41, adapted to vibrate on pivot pins 42, projecting inward from ears 26^c that extend rearward from the lower end portion of the bracket 26. Fixed to the rocker 41 which is preferably the style now employed in the Smith Premier No. 60 machine and extending downward below the pivotal axis thereof is an arm 43 which at its lower end carries a laterally extending cross pin 44, which provides means for connecting the rocker with the universal bar mechanism at the right of the arm 43 and with the space bar at the left of said arm.

In the present instance the universal bar mechanism is adapted to be actuated by the type bars. The universal bar 45 is arcuate in shape and is mounted or supported on the type bar segment 12, being housed in a slot 46, cut in the rear of said segment and so located that the forward edge of the universal bar is adapted to be engaged and actuated by contact faces 10^a on the type bars 10 as they approach the printing point on the platen. The universal bar when thus actuated is adapted to be moved rearward, being supported and guided in the usual way by devices shiftable with the segment, one of the guiding devices being a pin 47 which projects forward from an ear 48, integral with the universal bar 45, said pin having a sliding fit in a hole or guide opening 49 in the segment. The universal bar has rearwardly extending side arms 50, each pivotally connected at 51 with the forked end of a crank arm 52, extending upward from a rock shaft 53. The rock shaft 53 is pivoted on end pivots supported by arms 54 which are adapted to shift with the type bar segment during case shifting operations. Rigid with the rock shaft 53 is an arm 55, carrying a pivot 56 on which is supported a triangular plate 57 slotted at 58 to receive a clamping screw or device 59 that is carried by the arm 55 and serves to secure the pivoted plate 57 in adjusted relationships therewith. At its forward end portion the plate 57 carries a lateral pin 60 which cooperates with the forward slotted end of a link 61. The construction involving the adjustable plate or pivot carrier 57 is the invention of J. B. 130

Holden and is fully disclosed and claimed in his prior application Sr. No. 661,618, filed September 8, 1923. The rear end of said link 61 is slotted to fit over and cooperate with a circumferential groove 44^a in the right-hand end portion of the pin 44, said link connecting the oscillator, comprising the rock shaft 53 and its crank arms, with the dog rocker 41. The construction is such that when one of the type bars 10 is actuated to print, the contact face 10^a engaging with the universal bar 45 will move the latter rearward and rock the shaft 53 so as to swing the arm 55 rearward and downward, this motion being transmitted to the plate 57, fixed to and carried by said arm so that the pin 60 acting against the link 61 will thrust it rearward. This thrust being transmitted to the pin 44 and arm 43 will rock the rocker 41 and cause the dogs 39 and 40 to cooperate with the escapement wheel. The parts will be restored to normal position by springs not herein shown, the result being that at each type bar actuation the escapement devices will coact to afford a unit of letter space movement of the platen carriage and platen.

The escapement mechanism is also adapted to be actuated by the space bar or key 62. Said space bar is comprised in a space bar frame which further includes parallel side arms or levers 63 which are curved upward at their front ends and connected by the space bar 62 which extends cross-wise of the machine between them. The rear ends of the arms 63 are connected by a squared cross bar 64. The upper edges of the side arms 63 are formed with semi-circular seats or depressions 65 to cooperate with the under side of a pivot rod or shaft 66 that is mounted at its ends on supports 67. The rod 66 may be stationary but in the present instance I prefer to make use of the rock shaft of the case shifting mechanism. In order to maintain the space bar frame in cooperative engagement with the pivot rod or shaft 66, adjustable bearing members in the form of plates 68 are slidably or adjustably supported on the arms 63. Each plate or slide 68 is formed with a rearward extension or horn 69, the under side of which is shaped to coact with the top face of the pivot rod 66. In addition each of the slides or catches 68 is formed with top and bottom laterally bent lips 70 and 71 which fit over the associate arm 63, the said lips coacting with the top and bottom edges of the arm 63 so as to hold the bearing plate 68, 69 in fixed relationship therewith after said bearing plate has been secured in place. For this purpose the plate is formed with an elongated slot 72 which receives headed screws 73 that are threaded into the arms 63. The construction is such that when the space bar 62 is depressed it will rock the

space bar frame on the pivot rod 66, the bearing seats 65 and the extension 69 so cooperating with said rod that they almost completely surround it and provide bearings for the space bar frame thereon. However, by removing the rear screws 73 and loosening the forward screws the plates 68 may be slid forward on the arms 63, freeing the space bar frame so that it may readily be removed from the machine without disturbing the rod 66. This is a useful improvement since in prior constructions it has been necessary to go to the trouble of removing the rod or support in order to remove the space bar frame. The upward movements of the space bar frame are limited by stop devices comprising an arm 74 secured to the under side of the space bar 62 and provided with a pad 75 which is normally maintained in contact with the front portion of the base 1 by springs 76 which bear on the arms 63 in rear of the pivot rod 66. Downward movements of the space bar 62 are limited by a stop member 77 secured by a screw 78 to the front portion of the base 1. Fixed about centrally to the cross bar 64 is an angular arm or member 79 which extends rearward from the bar 64 and is bent or curved upward, its upper end carrying a lateral headed pin 80 which cooperates with the slotted rear end of an arm 81 that is adjustably secured to an angular lever 82. The said lever 82 is fulcrumed on a screw pivot 83 that is threaded into a downward extension 26^a of the bracket 28. The end or hip portion 82^a of the upper arm of said lever 82 is adapted to contact with the cross pin 44 which as shown in Fig. 3 is extended laterally leftward into the plane of said arm 82. The construction is such that when the space bar 62 is depressed it will rock the space bar frame on the rod or axis 66, swinging upward the cross bar 64 which carries with it the arm 79 and pin 80, the motion of the pin being transmitted to the lever member 81, 82, the upper lever arm acting on the dog rocker to cause the escapement dogs in cooperation with the escapement wheel to afford a feed movement of the carriage and platen. By reason of the pin-and-slot connection between the link 61 and the rocker arm 43, said link and the connecting universal bar devices will not be affected when the dog rocker is actuated from the space bar by the lever 82. The line lock mechanism is operated by contact devices supported on a toothed bar 84 arranged about the upper track bar 4 and pivotally supported at its ends on pivots 85 secured in lugs 86 projecting upward from the track bar. Adjustable on the stop bar 84 are a number of contact devices or stops including the one numbered 87 which is provided with two contacts or projections 88 and 89, the contact 88 being effective to

4

operate the bell ringing mechanism not shown, while the other contact 89 actuates the line lock mechanism. Mounted adjustably on the bar 84, to the left of the device 5 87, is a contact device or stop 90 provided with a lug or stop proper 91 which cooperates with the line lock mechanism to provide a final stop for the line. There may also be provided a stop member 92 having a 10 stop lug 93 and secured by screws 94 to the front of the track bar 4 for the purpose of preventing accidental displacement of the carriage from its trackways in co-operation with the upstanding stop 95 secured to the front of the carriage bar 7 by screws 96. Integral with the stop 95 is a 15 stop 97 which cooperates with an oppositely disposed stop lug 98 on the carriage to limit movements of the carriage-carried line lock 20 stop member or contact. Said member in the present instance is in the form of a bell crank 99 having an upstanding arm 100 and a rightwardly extending horizontal arm 101, terminating in a rearward projection 102. 25 Said bell crank or lever 99 is pivoted at 103 on the carriage bar 7. The upright arm 100 of the bell crank is confined loosely between the lugs or stops 97 and 98 which limit its pivotal movements, said bell crank being 30 normally maintained against the stop 97 by a spring 104. The upper end or tip of the bell crank has a path of movement which is intersected by the projections or contacts 88, 35 89 and 91, rendering them effective during the carriage travel to turn the bell crank and throw the arm 101 downward. The back faces of the contacts 88 and 89 are beveled, adapting them to cam the bar 84 on its pivots, so that return movements of the carriage 40 will not be obstructed.

The extension 102 of the bell crank constantly overlies the upper edge of a bar or bail 105 arranged in front of and parallel with the lower track bar 5, said bail having 45 rearwardly bent ears which receive pivot screws 106 threaded into the track bar 5. A leaf spring 107 secured to the left-hand side of the top plate by screws 108 maintains the bail 105 in normal position and 50 restores it after actuation. Near its middle the bail 105 is formed with a rearwardly bent finger 109 which engages with a line locking device in the form of a hook member 110 pivoted at 111 on the track bar 5 and 55 provided to the left of its pivot with an extension or finger 112, which overlies and is normally adapted to rest on the finger 109, which thus sustains the hook member in the inclined position of Fig. 3, maintaining 60 the lower end or engaging portion 113 in inoperative position. When released the member 110 swings through the force of gravity rightward about the pivot 111 to render the hook or engaging portion 113 effective. Said hook is adapted to coact with 65 an arm or stop device 114 secured by screws 115 to an arm 116 rigid with and projecting rearward from the rock shaft 53. The arm 114 terminates at its rear in an enlargement or head portion 117 which is cut out 70 as indicated at 118 to provide a contact edge or face 119 that is adapted to engage with the hook when the parts are in upper case position. Normally or in lower case position the hook 113 when swung to operative position 75 will cooperate with the under edge of the arm 114 to prevent the arm from swinging downward, which in turn will block or lock the rock shaft 53 and connected parts. It will be recalled that when 80 a type bar segment is shifted downward to upper case position the universal bar mechanism including the rock shaft 53 will move with it to a lower position. Such movement of course will be participated in by 85 the arms 116 and 114, as a result of which the contact surface 119 will be lowered into position where it will cooperate with the line lock hook 113 when it swings over into operative position. Such swinging movements will take place under the influence of gravity when the hook member 110 is 90 released by the sustaining finger or abutment 109; or in other words when the bail 105 is forced downward against its spring 95 107 through the action of the bell crank 99. Said bell crank in turn will be rocked or swung on its pivot 103 when the carriage in the course of its leftward movement brings the tip of the arm 100 first 100 into engagement with the contact 88 and subsequently with the contact 89. The contact 88, however, is of such height in relation to the tip of the arm 100 that it will only swing the bell crank to a slight extent, 105 this being sufficient to actuate the bell mechanism but not to render the hook member 110 effective. After the bell crank 99 is released by the contact 88 it will subsequently engage with the contact 89, resulting 110 in the operation above outlined, whereby the bail 105 is swung downward on its pivots 106, releasing the member 110 and causing the hook 113 to engage with the arm 114, thereby holding the universal bar 45 115 against movement and consequently locking the type bars and preventing them from printing.

With the parts locked through the coaction of the arm 100 with the contact 89, 120 while it was impossible in the prior construction to actuate the type bars, due to the blocking of the universal bar, it was nevertheless possible under a comparatively heavy stroke to spring the parts sufficiently to cause the dog rocker 41 to vibrate and effect an operation of the escapement mechanism, this resulting sometimes in causing a blank in the line of printing where none was intended or desired. To overcome this defect 125 130

I provide in the present construction for locking the escapement mechanism itself against operation by devices distinct from the type-bar line-lock devices. The escapement line lock mechanism, while highly effective, is quite simple and inexpensive, comprising few parts and being applicable to the prior construction without requiring material alteration. The escapement line lock devices comprise an angular member or arm 120, comprising a securing portion or base 121 from the left end of which is bent horizontally forward an extension 122 which is offset inward or towards the right end, terminating in a forwardly extending and downwardly bent contact 123. The member 120 is secured by headed screws 124 to the front face of the dog rocker about in the horizontal plane with its pivotal axis, the screws being threaded through the base portion 121 of said member 120. As will be seen from Fig. 3, the contact 123 is about in the fore-and-aft vertical plane of the head 117 and the engaging faces thereon. The contact 123 is adapted to coact with a contact which is preferably the offset upper end 125 of an arm or device 126 which is secured by headed screws 127 to the rear face of the depending arm of the hook member 110. Normally the contact 125 is disposed at the left of the contact 123 so that the path of the latter is unobstructed during vibrations of the dog rocker on which it is mounted. However, when the line lock hook member 110 swings over to operative position, due to so that thereafter the forward swing of the rocker 41 will be prevented by the engagement of the contact 123 with the contact 125. Thus, the escapement mechanism is locked against operation by one set of line lock devices 123 and 125 at the same time that the type bars are locked by another set of line locking devices 114 and 113. However, the parts are so related preferably that one set by which the type bars and universal bar are locked, only comes into use under ordinary strokes on the keys, the second set of line locking devices whereby the dog rocker is locked, becoming effective under an abnormal or heavy stroke. This construction prevents undue strain on the dog rocker and its connections. The devices 123 and 125 are in effect extensions respectively of the dog rocker and the hook member 110, 113, and may if preferred be formed integrally therewith.

In the prior construction disclosed in my aforesaid application Sr. No. 652,683, there was provided a separate line locking device for the space bar train, but by my present invention this separate device is dispensed

with and the space bar is locked and prevented from actuating the escapement mechanism by the contacts or line lock devices 123 and 125. In other words, these devices are effective to lock the escapement mechanism from operation both by the printing keys and the space bar. 70

As in the prior construction, after the line lock mechanism has become operative through the coaction of the arm 100 and the contact 89 the parts may be released to afford the printing of additional characters by swinging the stop bar 84 on its pivots, lifting the contact 89 out of the path of the arm 100, thus permitting additional feed movements 80 of the carriage in leftward direction until the final arrest by the contact 91. It is not deemed necessary to go into further detail of the line locking operations and the arresting of the carriage and platen effected by the described contacts, since the trains of mechanism operate in substantially the manner specified in my prior application. 85

Various changes in construction may be made, and some of the features of the invention may be employed without others, all without departing from the spirit and scope of the invention. 90

What I claim as new and desire to secure by Letters Patent, is:— 95

1. In a typewriting machine, the combination of a space bar frame comprising side arms and a connecting space bar; a pivot rod; and plates detachably secured to said side arms for retaining said frame on said pivot rod. 100

2. In a typewriting machine, the combination of a space bar frame, a pivot rod, and parts relatively movable on said frame for pivotally engaging said rod. 105

3. In a typewriting machine, the combination of a pivot rod, and a space bar frame pivotally mounted thereon, said frame being provided with relatively movable parts pivotally cooperating with said frame and affording ready detachment of said frame from said rod without disturbing said rod. 110

4. In a typewriting machine, the combination of a space bar frame comprising parallel arms and connecting cross bars, a pivot rod for said frame, and slides detachably mounted on said frame, said slides being formed with seats to engage the upper side of said rod, and said parallel arms being provided with oppositely formed seats to engage the under side of said rod, the seats being relatively movable to afford detachment of the frame without disturbing its pivot rod. 115

5. In a typewriting machine, the combination of a space bar frame comprising a pair of parallel side arms, and a space bar connecting said arms, a pivot rod for said frame, said side arms being formed with depressions to cooperate with the under side 120 125 130

- of said pivot rod, bearing plates slidably mounted on said side arms and provided with extensions shaped to engage with the upper side of said pivot rod to support said frame theron and prevent its accidental displacement, and screws for securing said bearing plates to said side arms, said screws when loosened permitting said plates to be moved to free said space bar frame from said pivot rod.
6. In a typewriting machine, the combination of a travelling carriage, a rack thereon, a feed pinion engaging said rack, a shaft with which said pinion is rigid, a fixed bearing for said shaft, an escapement wheel, a quill surrounding said shaft and to which said wheel is fixed, and key controlled escapement dogs cooperative with said escapement wheel, said quill cooperating with the said bearing to prevent endwise movement of the shaft in one direction, endwise movement in the opposite direction being prevented by co-operation of said feed pinion with said bearing.
7. In a typewriting machine, the combination of a travelling carriage, printing instrumentalities, escapement devices comprising a dog rocker, a universal bar connected to said dog rocker and operative by said printing instrumentalities, a space bar connected to said dog rocker, line lock devices for said universal bar, and separate lock devices for said space bar directly effective on said dog rocker.
8. In a typewriting machine, the combination of a travelling carriage, printing instrumentalities, escapement devices comprising a dog rocker, a universal bar connected to said dog rocker and two sets of line locking devices, the first set only coming into use under ordinary strokes on the printing keys, the second set of line locking devices coming into use under abnormal heavy strokes.
9. In a typewriting machine, the combination of a carriage, type bars, an escapement mechanism, a space bar, devices to lock the type bars against printing at the end of a line, and separate devices for locking the escapement mechanism to prevent a feed movement of the carriage at the end of a line, said separate devices being also effective to prevent the space bar from actuating the escapement mechanism.
10. In line lock mechanism for type writing machines, the combination of devices to lock the type bars from printing at the end of a line, and separate devices for locking the escapement mechanism to prevent a feed movement of the carriage at the end of the line.
11. In line lock mechanism for typewriting machines, the combination of a type bar operated universal bar, escapement mechanism comprising a pivoted dog rocker, line lock devices for said universal bar, and separate line lock devices for said dog rocker.
12. In line lock mechanism for typewriting machines, the combination of a type bar operated universal bar, escapement mechanism comprising a pivoted dog rocker, line lock devices for said universal bar and separate line lock devices for said dog rocker, said separate devices being controlled by both the printing keys and the space bar of the machine.
13. In a typewriting machine, the combination of a travelling carriage, a line locking hook, printing instrumentalities, a universal bar actuated thereby, a rocking arm connected to said universal bar and co-acting with said hook to lock the printing instrumentalities against operation, escapement devices for said carriage comprising a dog rocker, and a device rigid with said dog rocker for co-acting with said line locking hook to lock said dog rocker against operation.
14. In a typewriting machine, the combination of a travelling carriage, a line locking hook member, printing instrumentalities, a universal bar actuated thereby, a rocking arm connected to said universal bar and co-acting with said hook member to lock the printing instrumentalities against operation, escapement devices for said carriage comprising a dog rocker, and a device rigid with said dog rocker for co-acting with said line locking hook member to lock said dog rocker against operation, the printing instrumentalities being locked at the end of a normal key stroke, the locking device on the dog rocker only coming into play under abnormal key depressions.
15. In a typewriting machine, the combination of a travelling carriage, cooperative contacts one on the carriage and one on the frame, escapement devices comprising a dog rocker, a type-bar-operated universal bar, a rock shaft connected therewith, an arm on said rock shaft, a line locking hook rendered effective by said contacts to engage with and lock said arm, and an extension on said dog rocker cooperative with an extension on said hook.

Signed at the borough of Manhattan, city of New York, in the county of New York and State of New York, this 11th day of December, A. D. 1925.

EDWIN E. BARNEY.
